UNITED STATES PATENT OFFICE

LOCKWOOD B. ELLIS, OF DETROIT, MICHIGAN, ASSIGNOR TO GENERAL MOTORS CORPORATION, OF DETROIT, MICHIGAN, A CORPORATION OF DELAWARE

INTERNAL COMBUSTION ENGINE

Application filed July 20, 1925. Serial No. 44,761.

It is well known that in the operation of internal combustion engines, particularly those of the type used in automobiles, it has proven very difficult to maintain a supply of pure lubricant in the crankcase. Thus water, which is one of the products of combustion, and unburnt particles of fuel from the combustion chamber leak past the piston rings usually in the form of a vapor or gas, reaching regions of lower temperature and, particularly upon striking the relatively cool walls of the crankcase, condense and mingle with the fuel. The lubricating properties of the oil are thus greatly impaired and, if there is sulphur present, as where a fuel is employed which contains a slight proportion of this element, the sulphur uniting with the water will form an acid which will add corrosion to the bad effects of poor lubrication. The life of the motor is thus greatly shortened.

To overcome these difficulties I have devised the new method herein disclosed which is effective both to prevent contamination of the engine oil and to remove impurities and diluents which may have found their way therein. I have also preferably so applied the said method in my improved engine structure as to effect at the same time the efficient lubrication of certain of the engine parts.

To prevent contamination of the oil, I have provided means which serves to resist the passage of the leakage gases into the crankcase and to divert them therefrom preferably into the atmosphere. The specific means which I have employed consists of a head or body of air under pressure preferably acting in opposition to the flow of the leakage gases, said air discharging through an aperture in the cylinder wall and entraining and carrying with it in its outward passage the products of combustion which have leaked past the pistons. The stream of air thus performs a scavenging function.

In order that this scavenging stream may operate effectively it is desirable that the products from the combustion chamber shall be in the form of vapor or gas for the flowing air is relatively ineffective against particles of liquid. Now if the leakage gases are permitted to travel the length of the piston

skirt in the usual manner some condensation would take place owing to contact with the cooler portions of the piston skirt and cylinder wall. I have accordingly found it desirable to provide passages through the piston near the head for the discharge of these gases as well as excess lubricant and other fluids into the interior of the piston where the heat is sufficient to maintain them in gaseous condition. This also has the effect of relieving the pressure of the gases before they meet the scavenging air stream which also assists in vaporization. As another and additional means of reducing the pressure of the leakage gases I have also made use of the expedient described and claimed in my prior application Serial Number 730,458, filed August 6, 1924; that is, I have provided an annular groove in my piston, preferably in one of the lands thereof and have provided another aperture in the cylinder wall preferably smaller than the aperture previously referred to and located above the same, through which the leakage gases mixed with lubricant which find their way between the cylinder wall and the piston may discharge in a fine stream preferably into the compartment containing the valve mechanism, thus assisting in the lubrication of the latter.

Now it is apparent that there are a number of ways in which I may secure the desired pressure or head of air for my scavenging stream. Thus independent pump equipment may be provided for this purpose. However, I have preferred to make use of a pumping action inherent in the engine operation and in so doing have been enabled to accomplish the second object of my invention, that is, the removal of the diluents which may find their way into the crankcase under certain conditions. Thus at starting, with the engine cool, the leakage past the piston is in the form of condensed particles of water and fuel upon which, as previously stated, my scavenging stream has relatively slight effect. Also at very high engine speeds, as later described, there may be very considerable leakage extending usually, however, over but a short period of time. However, it may be that these diluents find their way into the crank-

case the action which will now be described provides effectively for their removal. The specific pumping action to which I have had resort is the centrifugal action of the rotating crank shaft which results in dragging the body of air in the crankcase around with the shaft and hurling or tending to hurl portions thereof in a tangential direction. Now the engine cylinders constitute pockets in which the tangentially hurled masses of air collect resulting in a building up of pressure therein which resists downward flow of the leakage gases and causes a discharge of air and the entrained leakage gases into the atmosphere, directly or indirectly, through the previously described openings in the cylinder walls. It is obvious that this discharge could continue for but a short period unless some means were provided for the introduction of air into the crankcase to take the place of that discharged and thus relieve the vacuum which tends to form as a result of the centrifugal action. I have accordingly provided air inlet ports in the crankcase, such ports being so arranged that the mass of air set whirling by the crank shaft induces a flow of air through the ports to take the place of that discharged through the openings in the cylinder walls.

The rapid rotation of the crank shaft produces a very complete mixture of the entering air with the engine oil and this aeration at the temperatures which prevail in the crankcase results in the air taking up a considerable portion of the diluents which may be present in the oil and carrying them away as vapors through the discharge ports in the cylinders. In this way the engine oil is subjected to a distilling action produced by the combination of heat and thorough mixing of the air and liquid. To enhance this action I have preferred to heat the incoming air prior to its entrance into the crankcase. By these expedients I have, by actual test, been able to eliminate in a very short time large quantities of diluents which had been mixed with the crankcase lubricant.

It must be obvious also that this distilling action may be used independently of the means for preventing the entrance of leakage gases into the crankcase.

One apparent difficulty which a construction such as described presents is that the outgoing stream of air will carry with it considerable quantities of lubricating oil and if means is not provided to effect a recovery of such oil and its return to the crankcase the entire supply will soon be ejected. I have accordingly provided means for separating the oil content from the issuing gases. While this may be done in a number of ways I have preferred to so locate the outlet in the cylinder wall that the issuing stream carrying with it particles of oil and leakage gases, is discharged into the compartment containing the

valve mechanism, upon which some of the oil particles collect thus assisting in the lubrication of the latter, and have provided the openings leading from said compartment into the atmosphere with baffles which also serve to intercept the oil, while the air and gases, freed from their oil content, are discharged through the openings. I have also preferably provided a drain opening through which the recovered oil may drip back into the crankcase. 75

While the air stream issuing from the valve chamber may, if desired be used for carburetion I have preferred to discharge it into the atmosphere, thus avoiding any possibility of clogging the carburetor passages 80 with the impurities carried by the air stream and also entirely removing from the engine undesirable combustion chamber products.

I shall now refer to the drawings wherein:

Figure 1 is a vertical section of a V-type 85 engine to which my invention is shown applied;

Figure 2 is an enlarged detail view showing more clearly the construction of piston and cylinder of Figure 1; 90

Figure 3 is a fragmental side elevation of the engine of Figure 1 showing one of the air inlet passages;

Figure 4 is a view corresponding to Figure 1 showing a modified construction; 95

Figure 5 is a horizontal section showing in detail the air cleaner used in connection with the construction shown in Figure 4;

Figure 6 is a vertical section of a vertical cylinder type of engine to which a modified 100 form of my invention has been shown applied.

I shall first describe the preferred form of my invention which is illustrated in Figures 1 to 3.

In Figure 1 I have shown a conventional V-type engine having the usual cylinders 10, pistons 11, connecting rods 12, crank shaft 13, crankcase 14, and compartments 15 for the valve mechanism. In this compartment will be located the valve springs, push rods, and associated parts as shown at the left of Figure 1. These parts have been omitted elsewhere so as to permit of clear illustration.

With this construction combustion chamber products consisting chiefly of burnt gases, water vapor, and unburnt fuel will, even with the best of seals, leak past the pistons into the crankcase where they will condense particularly by contact with the relatively cool walls of the crankcase and dilute the lubricating oil. To divert such products from the crankcase and effect their discharge into the atmosphere I have provided the cylinder walls with openings 21 which preferably have communication with the atmosphere through the intermediary of the valve compartments 15 and the louvers 25 in the outer walls or covers thereof, and have provided in the lower portions of the cylinders air 130

or gas under pressure which preferably opposes the flow of leakage gases into the crankcase. This air or gas discharges through the openings 21, entraining and carrying along with it the said gases, thus performing a scavenging function. For most effective operation I have found it best to locate the openings 21 fairly well up in the cylinder, the purpose of this being to accomplish the ejection of the leakage products before they have had opportunity to condense by contact with the cooler portions of the engine.

I have also preferably chamfered the inner edges of the openings 21 in order to reduce the noise of the outgoing streams of air and also to cause the resistance to outward flow of air to be less than resistance to inward flow; that is, I have found that by chamfering the inner ends of the openings 21 the resistance to the passage of gases is less when the flow is from the interior of the cylinder to the exterior than when the flow is in the reverse direction.

As a further aid in preventing condensation of the leakage gases which might occur as a result of their contact with the cooler portions of the piston skirt and cylinder wall, I may, as shown more clearly in Figure 2, provide my piston with passages near the head thereof leading into the interior thereof. These passages are preferably formed by slotting the lower piston ring as at 27 and drilling the bottom of the ring groove as at 28, and while they perform the usual function of providing for the return of excess lubricant which might otherwise work its way past the piston rings into the combustion chamber, they also serve for the discharge of leakage combustion chamber products into the interior of the piston where the intense heat which exists near the head maintains them in gaseous condition thus facilitating their ejection from the cylinder by the scavenging action of the air stream. This also effects a reduction in pressure of the leakage gases which, of itself, assists in maintaining them in a gaseous state and at the same time minimizes the possibility of any of said gases reaching the bottom of the piston skirt under sufficient pressure to overcome the counter-pressure of the scavenging air stream.

It will also be noted by reference to Figure 2 that I have provided a reservoir in the piston skirt to receive leakage gases and excess lubricant, this reservoir preferably taking the form of a groove 31 in the lower land. I have also provided openings 32 in the cylinder wall, one of which is shown in Figure 1, these openings being smaller than the openings 21 and above the latter. The groove 31 and openings 32 operate in the same manner as similar parts disclosed and claimed in my prior application Serial Number 730,458, to which reference has previously been made;

that is, when, during the travel of the piston, the groove 31 registers with the openings 32 the pressure of the leakage gases contained within the groove results in the projection of a fine spray or mist, rich in oil, into the valve compartment. This assists in the lubrication of the valve mechanism. At the same time the arrangement also acts to reduce the pressure of the leakage gases and thus tends to prevent their condensation, and consequently supplements the action of the grooved rings 27 and openings 28 previously described. While a single opening might suffice for the discharge of products from the groove 31 and for the passage of the outgoing air stream, I have found it preferable to provide the additional smaller openings 32 in order to accentuate the spraying action upon discharge of the contents of the groove.

It will now be understood that by building up pressure in the lower portions of the cylinders air is intermittently ejected through the apertures 21 in the cylinder walls into the valve compartments, entraining with it in its passage leakage products particularly such as escape through the apertures 27-28; in its flow through the valve compartments it combines with the products discharged through the openings 32 and passes outwardly through the louvers 25 preferably into the atmosphere, baffles 53 serving to separate particles of oil from the air stream. The oil thus intercepted collects in the bottom of the valve chamber and drains back into the crankcase through the apertures 30. It is obvious, of course, that any well known type of oil separator may be substituted for baffles 53, if desired.

I shall now describe the means by which I secure the desired air pressure for producing the scavenging stream. For simplicity, as well as to secure certain advantages to which I have previously called attention and shall now again refer, I have found it desirable to make use of a pumping action inherent in the engine. The pumping action which I have selected is a result of the rotation of the crank shaft. The effect of the rotation of this shaft is to drag around with it the body of air or gas as well as lubricating oil and other fluids contained in the crankcase and to tend to hurl them in tangential directions, thus producing a region of low pressure adjacent the axis of the crank shaft and a region of high pressure remote from the axis. The engine cylinders constitute pockets which receive tangentially hurled air so that a pressure is built up therein which, obviously, is in a direction tending to resist the downward flow of the products of combustion into the crankcase.

By providing a properly arranged inlet air may be drawn in to replace that discharged through the apertures 21 and thus a circulation of air through the crankcase

may be obtained. Thus I have provided air inlet passages 50, provided with baffles 51-52 so that their inner openings extend in the direction of rotation of the crank shaft, whereby the latter exerts an aspirating action upon them; in other words, produces a low pressure area adjacent their inner ends thus drawing air into the crankcase.

In addition to merely drawing air into the crankcase and discharging it through the apertures in the cylinders the rotation of the crank shaft results in a thorough mixture of the entering air with the crankcase contents which results in the vaporization of the diluents mixed with the lubricating oil. This vaporization is, of course, facilitated by the heat normally reaching the crankcase from the combustion chamber but I have preferred to increase the evaporative action by heating the air prior to its admission to the crankcase. In the embodiment shown I have accomplished this by running air inlet passage 50 along the hot cylinder walls as shown on the drawings.

It will also be noted that the outer ends of the air inlet passages 50 open in the direction of flow of the air blast produced by the action of the customary cooling fan, and indicated by the arrows 55, so that there is a selection of clean air for use in the crankcase.

Another object incidentally accomplished by the construction just described is this; the engine is automatically supplied with what constitutes an effective air cleaner. This comes about from the fact that at very high engine speeds the pistons and rings vibrate to such an extent as to be relatively ineffective and allow the passage into the crankcase of considerable qualities of combustion gases under high pressure. This pressure is great enough to overcome the pressure of the centrifugally hurled masses of air with the result that there is an actual discharge of gases through the passages in the crankcase which ordinarily serve for the intake of air. This action is undoubtedly increased by the aspirating effect of the air stream due to the fan blast and the motion of the vehicle acting upon the outer ends of passages 50. The discharged gases carry the usual oil content so that the walls of the inlet passages are liberally sprinkled or moistened with oil. This oil serves to trap dust which is carried in with the entering air in the subsequent normal operation of the engine. When the engine again runs at very high speeds this oil coating is renewed. However, any usual type of air cleaner may also be employed at the intake openings if desired.

By utilizing the motion of the crank shaft for pumping I obtain the additional advantage that the pumping action is substantially equally effective at each of the cylinders; that is, each crank shaft throw will produce the pumping action for its particular cylinder or

cylinders, and the pumping actions so produced will necessarily be substantially equally effective. This means that the pressures in the various cylinders tending to force air out through the apertures therein will be substantially equivalent with the result that there will be an even distribution of the air stream in its passage through the crankcase from the air inlets to the air outlets.

The action of the crank shaft in pumping depends upon its displacement. Hence I have found that most effective pumping action is obtained by the use of a relatively small crankcase so that the displacement caused by the rotation of the crank shaft is a considerable percentage of its volume. The action is also promoted by the use of a crank shaft having counterweights, these counterweights serving their customary purpose but also serving to increase the crank shaft displacement and hence increasing the pump capacity.

In Figure 4 I have shown a slightly modified form of my invention. In this embodiment the air entrance passages 20 lead to points adjacent the center of the crank shaft which is a low pressure area as previously described. Likewise air cleaner 40 is shown applied to the outer end of the air intake passage. This cleaner is shown in detail in Figure 5 and comprises a tubular member 41 surrounding the outer end of the air inlet passage 20 and tapering in the direction of the air flow resulting from the action of the usual cooling fan and indicated by the larger arrows. Disposed centrally within the tubular member 41 is a cup-shaped member 42, this member shielding the inlet passage 20 from the direct action of the fan blast. With this arrangement the heavier particles of dust and the like are carried beyond the passage 20 resulting in a selection of relatively clean air for the crankcase.

It will also be noted that in Figure 4 as well as in Figure 6 I have substituted baffles 26 for the single baffle 53 shown in Figure 1.

Figure 6 illustrates my invention applied to a vertical type engine. This figure also shows apertures 22 in the piston skirt for registration with the aperture 21 whereby the frequency of the pulsations of the discharging air stream is increased. I have omitted openings 32 in this embodiment.

I claim:

1. The combination of an internal combustion engine comprising a crankcase, a cylinder and a piston operating in the cylinder, means for lubricating the piston, and means for passing a stream of air through the lower portion of the cylinder, said stream discharging outwardly of the cylinder and carrying with it combustion chamber products which have leaked past the piston thus preventing their entrance into the crankcase.
2. The combination of an internal com-

bustion engine comprising a crankcase, a cylinder and a piston in the cylinder, said piston being lubricated from the crankcase, means for passing a stream of air through 5 the lower portion of the cylinder, said stream discharging outwardly of the cylinder and carrying with it combustion chamber products which have leaked past the piston thus preventing their entrance into the crankcase, 10 and means for separating particles of oil from the outgoing air stream.

3. The combination as set forth in claim 2, said engine being formed to provide a chamber adjacent the cylinder into which the air 15 stream discharges, valve mechanism in said chamber.

4. The combination of an internal combustion engine comprising a crankcase, a cylinder and a piston, said piston being 20 lubricated from the crankcase, means for establishing a stream of air through the lower portion of the cylinder, said stream discharging outwardly of the cylinder and carrying with it combustion chamber products 25 which have leaked past the piston thus preventing their entrance into the crankcase, a chamber adjacent the cylinder into which the air stream discharges, mechanism in said chamber, means for separating the particles 30 of oil from said air stream prior to its discharge from said chamber, and means for returning said particles of oil to the crankcase.

5. The combination of an internal combustion engine comprising a crankcase, a cylinder and a piston, means for building up pressure in the air in the lower portion of the cylinder to resist the passage of combustion chamber products past the piston and into the 40 crankcase, and a port in the cylinder wall for the discharge of air therethrough, said discharging air stream carrying with it said combustion chamber products.

6. The combination as set forth in claim 5, 45 the said port in the cylinder wall lying within the limits of travel of the piston.

7. The combination of an internal combustion engine comprising a crankcase, a cylinder and a piston, means for lubricating 50 the piston from the crankcase, means for building up pressure in the air in the lower portion of the cylinder to resist the passage of combustion chamber products past the piston and into the crankcase, a port in said cylinder wall for the discharge of said air therethrough, said discharging air stream carrying with it said combustion chamber products and thus preventing their entrance 55 into the crankcase, a chamber into which said outgoing stream of air discharges, and mechanism in said chamber whereby the mist of oil carried by said stream effectively lubricates said mechanism.

8. The combination of an internal combustion engine comprising a crankshaft, a crank- 60

case, a cylinder and a piston in the cylinder, an opening in the crankcase so arranged as to be subject to aspiration as a result of the rotation of the crank shaft and an air discharge opening in the cylinder wall. 70

9. The combination as defined by claim 8, said discharge opening in the cylinder wall lying in the path of travel of the piston so that it is intermittently uncovered.

10. The combination of an internal combustion engine comprising a crank shaft and a crankcase, an air entrance opening for said crankcase, said opening being so arranged with respect to said crank shaft that a low pressure area is created at the inner end thereof by the rotation of the shaft whereby air is drawn into said crankcase, and an air discharge opening for said crankcase, said air discharge opening being so arranged with respect to said crank shaft that the rotation of the latter will produce a high pressure area adjacent the inner end thereof for the discharge of air therethrough. 75 80 85

11. The combination of an internal combustion engine comprising a crank shaft, a crankcase, cylinders, and pistons in said cylinders, an air inlet for said crankcase, said inlet being provided with a baffle to prevent the discharge of air therethrough, and apertures in said cylinder walls for the discharge 90 95 of air therethrough.

12. An internal combustion engine comprising a crankcase having an air inlet, cylinders and pistons in said cylinders, means for causing a substantially continuous flow 100 of air into said crankcase, through said inlet, said cylinders being provided with openings located within the piston stroke for the discharge of air therethrough when uncovered by said pistons. 105

13. An internal combustion engine of the V-type having the usual crankcase, cylinders, and valve chambers arranged on adjacent sides of the angularly disposed cylinders, an air inlet for said crankcase, passages providing direct communication between said cylinders and said valve chambers, air outlets from said valve chambers, and means for establishing a flow of air from said inlet through the crank case and said passages to 110 said outlets. 115

14. An internal combustion engine comprising a crankcase, a cylinder, a piston in the cylinder, said cylinder wall being provided with a port for the discharge of leakage combustion chamber products from the cylinder in their passage past the piston, said cylinder being provided with a second port below said first named port, means for causing a flow of air through the lower portion of the cylinder and outwardly through said second named port. 120 125

15. An internal combustion engine comprising a crankcase, cylinders and pistons in the cylinders, the skirts of said pistons 130

being apertured for the discharge of leakage combustion chamber products from the space between the pistons and the cylinder walls whereby their pressure is relieved, ports in the cylinder walls within the limits of the stroke of the pistons and means for passing a stream of air from the crankcase outwardly through said ports whereby the leakage products of combustion are entrained therewith and prevented from entering the crankcase.

16. An internal combustion engine comprising a crankcase, a cylinder, a piston in the cylinder, means for discharging outwardly of the cylinder under their own pressure, combustion chamber products and excess lubricant from between the piston and the cylinder wall, said means being effective adjacent the hotter portions of the piston whereby said products are maintained in gaseous condition, means for causing a flow of air from the crankcase through the lower portion of the cylinder and outwardly thereof, said air stream preventing the passage of said products into the crankcase and entraining them with it.

17. The combination as set forth in claim 16, and mechanism arranged adjacent said discharge means whereby it is effectively lubricated.

18. The combination as set forth in claim 16, and mechanism arranged adjacent said discharge means and in the path of said issuing air stream whereby it is effectively lubricated.

19. An internal combustion engine comprising a crankcase, cylinders, pistons in the cylinders, said pistons being provided with annular reservoirs, ports in the cylinder walls for communication with said reservoirs in the course of the stroke of the pistons whereby the contents of said reservoirs may be discharged therefrom, the skirts of said pistons being apertured, and means for passing a stream of air from the crankcase through the lower portions of the cylinders within the limits of the piston stroke for entraining with it the released leakage products and lubricant.

20. The combination as set forth in claim 19, mechanism arranged in the path of the issuing air streams whereby said mechanism is effectively lubricated, oil traps in the paths of the air streams, and means for returning the collected oil to the crankcase.

21. The combination of an internal combustion engine having a crank shaft, a crankcase for containing lubricant, cylinders, and pistons in the cylinders, and means for introducing air into said crankcase so as to be entrained by the action of the rotating crank shaft, said cylinder walls being apertured at points within the stroke of the pistons, said stream of air discharging through said apertures.

22. The combination as set forth in claim 21, and means for heating the air prior to its introduction into said crankcase.

23. The combination of an internal combustion engine having a crank shaft, a crankcase, cylinders and pistons in the cylinders, a passage for the introduction of air into said crankcase so as to be entrained by the action of the rotating crank shaft, means for heating the air in its travel through said passage, said cylinder walls being apertured at points within the stroke of the piston and said stream of air discharging through said apertures, valve mechanism arranged in the path of movement of the issuing air stream, and means for separating particles of oil from the stream and returning said oil to the crankcase.

24. The combination as set forth in claim 23, said engine being provided with a fan to produce a cooling flow along the engine housing and said air intake passage facing away from the fan blast.

25. In an automobile, the combination of an internal combustion engine having the usual cylinders, pistons in the cylinders, a crankcase serving as a lubricant reservoir, said engine being exposed to a cooling air flow in normal operation, said crankcase being provided with an air inlet facing in a direction to be subject to the aspirating action of the passing air stream, said cylinders being provided with apertures for the discharge of air from the crankcase and means for normally causing a flow of air through the crankcase and outwardly through the apertures.

26. In an automobile, the combination of an internal combustion engine having the usual crankcase serving as a lubricant reservoir, cylinders, pistons in the cylinders, a valve chamber alongside the cylinders, valve mechanism in the chamber, said engine being exposed to the usual cooling flow of air in normal operation, said crankcase being provided with a rearwardly facing air inlet subject to the aspirating action of the air stream, ports directly connecting the cylinders and the valve chamber, said chamber being provided with an air outlet.

27. An internal combustion engine comprising a cylinder and a piston, a plurality of successively operating means for the discharge of leakage combustion chamber products during their passage past the piston thereby assisting said products in remaining in a vaporous or gaseous state, and means for preventing the entrance of said products into the crankcase and diverting them therefrom, said successively operating means comprising apertures in the cylinder wall and in the piston.

In testimony whereof I affix my signature.

LOCKWOOD B. ELLIS.
